UNITED STATES PATENT OFFICE.

EDWIN K. LUNDY, JR., OF CHICAGO, ILLINOIS.

REINFORCEMENT FOR CELLULAR PACKING STRUCTURES.

Application filed April 9, 1921. Serial No. 459,853.

To all whom it may concern:

Be it known that I, EDWIN K. LUNDY, Jr., a citizen of the United States, residing at Chicago, in the county of Cook and State 5 of Illinois, have invented a new and useful Improvement in Reenforcements for Cellular Packing Structures, of which the following is a specification.

My present invention relates to devices 10 for stiffening cellular packing structures, such as are used for packing and shipping eggs, or like articles, in order to protect the individual articles, which are sometimes highly fragile, from being broken through 15 contact with each other.

Such cellular structures are now generally formed from strips of straw-board, or other suitable materials, which are slotted usually through a portion of their width at regular 20 spaced intervals and assembled in parallel and intersecting rows. These structures must depend for their rigidity upon the stiffness of the straw-board, or other material of which the walls are fabricated, 25 which, while not very liable to longitudinal compression is extremely liable to lateral flexing which serves to shorten the transverse dimension of a row of cells thereby permitting the eggs or other articles contained 30 in the cells to shift and cumulate their movement and weight in the direction of any jar, which develops very much more compression than is desired, and which the contents is capable of withstanding, upon 35 certain of the articles and sometimes upon entire rows of articles, thereby entailing considerable breakage and resulting loss.

My present invention has for its object the stiffening and bracing of the interior walls 40 of a row of cells whereby the walls are reinforced against flexing, and the articles are prevented from accumulating their movement and weight against each other. Such cell-sections as have heretofore been referred 45 to are usually separated by "flats" interposed between different layer of cells. My invention, broadly speaking, contemplates the provision of a binder one portion whereof is to be inserted in one or more 50 individual cells and the other portion whereof either interlocks with the flat or extends to and is braced against the walls of the case or container in which the cells and flats are disposed. As will be obvious, this generic 55 idea is capable of divers applications,

some of which have been illustrated in the accompanying drawings, in which—

Figure 1 is a perspective of a cell-section and a portion of a flat with my reinforcing and stiffening structure interlocking there- 60 between.

Figure 2 is a blank or development of the interlocking device.

Figure 3 is a section on line 3—3, Figure 1, showing, however, a plurality of super- 65 posed cells and flats and the manner in which the egg or other contents of a cell assists in the interlocking feature.

Figure 4 is a plan of a structure similar to that shown in Figure 1, except that the 70 ends of the interlocking devices are mitered so that they may be arranged on all four sides of a cell-section.

Figure 5 is a blank or development of the interlocking device illustrated in Figure 4. 75

Figure 6 is a section on line 6—6, Figure 4.

Figure 7 is a blank or development of a form of interlocking structure adapted for engagement with one of the outer walls of 80 a cell-section.

Figure 8 is a fragmental section illustrating the assembly of the form shown in Figure 7 with a series of cell-sections and a flat. 85

Figure 9 illustrates a form in which the interlocking device engages with a single but interior cell and the edge of the flat and the manner of using a number of such forms in a single cell-section. 90

Figure 10 is a section on line 10—10, Figure 9.

Figure 11 shows a form in which the interlocking means comprises two centrally intersecting members provided with tangs for 95 engagement with each cell over which they respectively pass and a top element bracing against the sides of the case or container.

Figure 12 is a section on line 12—12, Figure 11. 100

Figure 13 is a plan or development of one of the bracing elements shown in Figure 11.

All of the forms of the bracing or reinforcing device shown in the several views 105 have one or more tongues or tangs 15 adapted, as the case may be, to extend downwardly into one or more cells of a cell-section and to be held in its downwardly inserted position by the egg or other con- 110

tents 16, as shown in Figure 3 of the drawings. The tongue or tongues 15 extend laterally from a body member 17, which extends to the edge of the case or container 5 and is then folded back upon itself to provide a lip 18 against which the edge of a flat 19 engages. It is obvious that one of the forms of reinforcing structure, shown in Figures 1 to 3, inclusive, may be provided 10 in opposite sides of each cell-section. The interlocking structure, shown in Figures 1 to 3, inclusive, while engaging with a pair of opposite edges of the flat, also is proportioned so that the ends of the portions 17 15 will extend between opposite walls of the case or container and will, therefore, provide considerable reinforcement transversely of, as well as between the edges co-acting with the flat.

20 The construction illustrated in Figures 4 to 6, inclusive, of the drawings, having mitered ends 20 is capable of engagement with all four edges of flat 19, and, as the flat is prevented from bending downwardly 25 by reason of the cell wall upon which it rests and is prevented from bowing upwardly both by the cell-walls and the weight of the articles resting upon it, a considerable degree of reinforcement is secured by this 30 structure.

The structure illustrated in Figures 7 and 8, while designed for assembly with the outside walls of a cell-section, may be proportioned so as to hold them under tension and 35 thereby prevent their flexing and the breakage incident thereto. This structure is characterized by a very narrow body member 21, the function and operation of the elements of this form being the same as that shown in 40 Figures 1 to 3.

The structure illustrated in Figures 9 and 10 involves only a single uniform strip of suitable reinforcement material 22 the tongue or tang 15 whereof is formed by 45 bending laterally one end and lip 18 whereof is formed by folding the other end in the opposite direction to the bend of the tongue or tang 15. This structure has such advantages as arise from its extreme simplicity 50 and may be easily formed to reinforce the centermost of the individual cells of a section. This form of structure should be used with four to each cell-section, as illustrated in Figure 9.

55 The structure illustrated in Figures 11 to 13, inclusive, has tangs 15 provided with what may be termed the lateral side of body member 17, the body member being proportioned and designed to fit or wedge between the opposite walls of a case or container. In this form a slot 23 is arranged at 60 the top of one of the central tongues 15 to accommodate the body portion of a similarly shaped transversely disposed reinforcing piece. The ends of the body piece may

be provided with lips 18, if desired, to engage with the flat, as in the other forms.

The structures heretofore described are placed in a suitable case or container fragmentally illustrated in several of the views 70 and designated by the numeral 14 which consists of the six ordinary walls of a rectangular box structure.

What I claim as new is:—

1. As an article of manufacture, a reinforcing device for cellular structures comprising a body element having a downwardly projecting tongue that enters a cell adjacent a wall thereof and a lip engaged by the edge of a flat disposed upon the top 80 of a cell-section.

2. In combination with cell-sections consisting of intersecting walls and a flat disposed upon the top of said walls, of a reinforcing device comprising a body element 85 having a downwardly projecting tongue that enters a cell flat against a wall thereof and a lip engaged by the edge of said flat.

3. In combination with a case, and tiers of cell-sections superposed therein, said cell-sections consisting of a plurality of walls arranged in parallel series the walls of said series intersecting, of separate reinforcing devices extending from opposite walls of said case and inserted flat against the walls 95 of said cell-sections.

4. In a cellular case, a cell-section comprising a plurality of intersecting walls, a flat upon the top of said cell-section, and reinforcing devices having members inserted 100 flat against the walls of said cell-section and having elements engaged by the flats.

5. A device of the kind described comprising a case, a cell-section therein comprising a plurality of intersecting walls, and 105 reinforcing devices having members inserted in the cells and flat against the walls thereof, said reinforcing devices being extended to engage the walls of said case.

6. As an article of manufacture a reinforcing device for cellular packing elements comprising a sheet having lateral extensions adapted to interfit respectively with the walls of the cells and the partitioning element between adjacent cell-sections. 110

7. In combination with cellular packing elements comprising intersecting walls forming cells and a partition above said cellular section, a reinforcing device comprising a sheet having folded portions adapted respectively to extend into the cells of said section flat against the walls thereof and to receive the edge of the adjacent partition. 120

8. In combination with cellular packing elements comprising intersecting walls forming cellular sections and partitions between adjacent cellular sections, and reinforcing devices comprising sheets having folded portions at each edge, one folded portion of each sheet adapted to extend into the 125

cells of its respective section flat against the walls thereof and the other folded portion of said sheet adapted to receive the edge of an adjacent partition.

5 9. In combination with cellular packing elements comprising intersecting walls forming cells and a partition above said cellular section, reinforcing devices comprising elements engaging the walls of the cell-section 10 and extended transversely of each side thereof to engage the respective edges of the partition whereby the partition, which is held against distortion by the cellular elements and their contents, prevents the 15 flexing of the intersecting walls of said cellular section.

10. As an article of manufacture a reinforcing device for cellular packing cases comprising a sheet having lateral extensions 20 upon one edge adapted to coact with the walls of the cells in said case and the opposite edge of said sheet co-acting with the walls of the case.

11. The combination with a cellular filler 25 including intersecting walls and a partitioning flat, of a reinforcing device therefor comprising a body element constructed to interengage with the partitioning flat and having means inserted between a cell 30 wall and the article contained in the cell.

12. A reinforcing device for cellular structures comprising a body element constructed to interengage with a partitioning flat dis-

posed upon the cellular structure and having means inserted between a cell wall and 35 the article contained in the cell.

13. A reinforcing device for cellular structures comprising an elongated strip of suitable material having a lip along one longitudinal edge for engagement with a partitioning flat and a tongue extended from the opposite longitudinal edge for insertion between a cell wall and the article contained 40 in the cell.

14. A reinforcing device for cellular structures comprising an elongated strip of suitable material one longitudinal portion 45 whereof interengages the adjacent portion of a partitioning flat and the opposite longitudinal portion of said strip is fitted between a cell wall and the article contained 50 in the cell.

15. As an article of manufacture a reinforcing device for cellular structures comprising a sheet of suitable material one 55 edge whereof is provided with a folded back lip and the opposite edge is provided with a plurality of laterally projecting tongues.

In testimony whereof I have signed my name to this specification, in the presence 60 of two subscribing witnesses, on this 6th day of April, 1921.

EDWIN K. LUNDY, JR.
